US0D1053664S

(12) **United States Design Patent** (10) Patent No.: **US D1,053,664 S**
Lee et al. (45) Date of Patent: ** Dec. 10, 2024

(54) **LID FOR BEVERAGE CONTAINER**(71) Applicant: **ENI-JR286, Inc.**, Torrance, CA (US)(72) Inventors: **Jesse C. P. Lee**, Torrance, CA (US);
George A. Patrikeyev, Santa Cruz, CA (US)(73) Assignee: **ENI-J286, Inc.**, Torrance, CA (US)(***) Term: **15 Years**(21) Appl. No.: **29/904,881**(22) Filed: **Oct. 12, 2023**
